Stephen H. Long U. S. Army 7570X

Letters Patent

the schedule referred to in the Letters Patent and making part of the same containing a description in the words of the said Stephen H. Long of his improvement in the construction of Boilers or Steam Generators and of Wheels for locomotive Steam Engines.

To all to whom these presents shall come. I doth it Known that I Stephen H. Long of the United States Army have invented certain new and useful improvements in the construction of Boilers, or Steam Generators, and of Wheels, for the Pennsylvania Locomotives and other Locomotive Steam engines and that the following is a full and exact description of my said improvements. In addition to my improvements in the construction of Boilers as specified in the first item of my Letters Patent under date of December 28th 1832. I claim the following improvements in the construction of Boilers and other apparatus appertaining to them as new and useful, to wit, 1st The introduction of flues or tubes passing longitudinally through that portion of each cylindrical boiler situated in rear of the fire place. For or to admit of this arrangement the lower half of each boiler is inclosed by a metal screen or plate of any convenient width, length, and of the boiler (say four to eight inches) and rising from the lower part or end of the boiler to a line or plane passing horizontally through the boiler at or a little below its centre. The sides of this niche or recess will of course be nearly semi circular and should be parallel to each other. The rearward of the fire place being provided with holes in which the tubes or flues are inserted. And that toward the front of the fire place being of similar form but destitute of perforation, for the reception of flues. The space above and between the sides of the niche presents a plain surface constituting a portion of the boiler. Hence the portion of the Boiler situated immediately above the

500

fire place or suitable of flues which those back of the fire place are supplied with a greater or less number of flues according to the size of the cylinders, of which the steam generator or boiler is composed which flues are contained in a segment of each cylinder occupying the lower half of the same. On that portion of each cylinder situated immediately above the fire place a smaller cylinder of sheet iron or copper serving as a steam chamber may be inserted. This cylinder may be of a size as large as can be admitted through the man. hole into that portion of the cylindrical boiler between the fire and the mouth in which there are no flues or tubes. The object of this small cylinder is not only to enlarge the steam room but to exclude from the boiler a considerable quantity of water which would otherwise be required. A free communication between the interior of each small cylinder and the upper part of the boiler in which it is situated is afforded by means of a tube rising from the bottom of the former and opening into the top or steam room of the latter. 2nd I also claim as a new and useful improvement in the construction of boilers for locomotive engines the introduction of a fire box adapted to two or more cylindrical boilers to be constructed and applied in the following manner viz. The front sides and back of the box are of the usual construction so far as relates to those portions of the same that are situated below the cylindrical boilers. The back sides nearly or quite to the bottoms of these boilers may rise to any convenient height not lower than a line ^{parallel} passing through the center of the same. The front may rise three to six inches or more above the tops of the cylindrical boilers. This as well as the other sides of the fire box is constructed of two plates or sheets of iron of suitable thickness, confined at suitable intervals together by means of stay bolts and other rivets and plates. The interior sheet or plate of the front is perforated with circular openings corresponding to each cylindrical boiler of a diameter about one inch less than that of the interior of the boiler. This plate is attached to the front end of

All the cylindrical boilers, by means of iron stay bolts, passing through the plate, and through a flange about one inch wide, having a recessed edge at the front end of each boiler, and made continuous with round the interior periphery of the boiler. These are fitted and afterwards calked in the usual manner. The plate forms a straight junction with the boilers. The interior side of the front is also perforated with openings after the manner of man holes in front of each boiler and corresponding to them respectively.

This arranged the front of the fire box will serve not only as a steam generator but as a conduit through which the materials to be conveyed into the cylindrical boilers, in a manner to keep them equally supplied and will at the same time serve to the purpose of a steam pipe leading from the cylindrical boilers, but from the fire box to the main steam pipe through which the steam is conducted to the working cylinders. The front of the fire box is also perforated as usual by one or more fire holes of suitable dimensions.

In reference to the arrangements of the several parts of the boiler as steam generator as above contemplated, it should be remarked that the chimney is situated at the rear or back end of the cylindrical boilers or at the end farthest from the fire place, also that the water to supply the boilers is conveyed from the fire pump through a tube which enters the back of the fire box a little below the cylindrical boilers.

3° of also claim as a new and useful improvement in the construction of boilers, for the purposes already mentioned, the application of an iron plate situated in rear of the fire box beneath the cylindrical boilers and about one inch from them, which iron plate may pass horizontally beneath the boilers with the space or spaces between them and may run either in a curve or in a oblique right line or slant from beneath the bottom of each cylindrical boiler to a horizontal iron bar passing through the centre of the cylindrical boiler. The margin of this plate may be attached to the outside of the boiler, or also to the back of the fire box by means of some bolts, otherwise.

The space between the boiler and ^{the} apron is intended as a flue through which a portion of the heated air etc is conducted from the fire place to the chimney.

The construction of the apron may be as follows. Two or more ribs of iron, about one inch square, are formed by bending them into a shape corresponding to a transverse section of the apron. These ribs are to be disposed in such a manner that one of them may occupy a position immediately back of the fire box and another a position directly below the rear or back end of the boiler. The residue should more than two be required occupying positions intermediate to those above designated all the ribs being parallel to each other, and having their ends attached to the outside of the boiler on the lines of contact between them and the margins of the apron. Upon these ribs both externally and internally thin sheets of iron are fastened by means of rivets passing through the ribs and the sheet. The spaces ~~open~~ or spaces between the sheets which spaces are of a thickness or depth equal to that of the ribs is filled with a lining or mixture of powdered charcoal and clay consisting of about three parts of the former to one of the latter or with some other suitable nonconductor of heat. The flue between the boiler & the apron as also the tubular flues within the cylindrical boiler are all open into a smoke box situated at the back end of the boiler from which the smoke etc together with waste steam from the working cylinders and from the safety valve are ejected vented by through a chimney rising from the top of the smoke box. The chimney is formed of two parts one of which is firmly attached to the smoke box and rises about eight feet above it and the other includes the former being of larger dimensions and of such a construction as admits of its being moved upward and downward on the part first mentioned. The movable part of the chimney is furnished with appropriate apparatus and fixtures by means of which it may readily be raised or depressed at the pleasure of the person in attendance and may as he may find it expedient be passed under bridges or through

turnally, or for the purpose of increasing the draft through the fire places. It is, moreover, claim as a new and useful improvement in the construction of boilers for steam engines, the discovery and application of a grate adapter in the use of anthracite coal. The construction of the grate is as follows, viz. The grate bars are introduced in a square or rectangular and movable frame of sheet iron about one fourth of an inch thick and of such dimensions in other respects, that it may enter freely into the lower part of the fire box heretofore described. The sides of the frame may be about five inches in depth, of which about two inches are made to enter the fire box. The grate bars are supported within the frame, one being of iron extending partly across the frame and resting in the side of the opposite sides. The position of the bars, with respect to the grate bars is rectangular beneath them and at so within about six inches of their ends. The beams are of a square or rectangular form supporting the grate bars upon one of their sides respectively. One of both of the beams is furnished with a journal at each end passing through the side of the grate frame by means of which an oscillatory movement may be communicated to one or both of the beams by means of a vibration or knock applied to one part of this beam, either externally or internally of the frame as may be found most convenient. By means of the oscillating of one or both beams a vibratory motion is communicated to the grate bars, which motion is rendered alternate between all the contiguous bars in consequence of the corners of the beam on its upper or bearing side being alternately truncated immediately beneath each grate bar.

The ends of journals of one of the beams, project through and beyond the sides of the grate frame far enough to enter steps or supports attached to the lower part of the sides of the fire box in which steps the beam is attached to brace and serves as an axle for the grate. By this means one side or end of the grate (together with the ash pan which is attached to the lower edge of the grate frame) may be let down at pleasure for the purpose of discharging at once the contents of the fire places, and again elevated for the reception of a new

charge office. This operation is facilitated by the aid of heavy
wedges and points appropriately adjusted for the purpose.
5. The claim is in a new and useful improvement in the
construction of wheels for Locomotives, steam engines, the application of
hubs of cast iron in connection with wooden wheels, each hub being
formed of two semicircular portions or segments of a circular form and
of suitable diameter and thickness, adapted to each other by means
of a socket in one of the segments, filled for the reception of a
annular iron projecting from the inner side of the other segment
through both of the said pieces transversely of the hub in the
direction of its axis. On the exterior segment of the hub and extending
by thereof is a ring or bar in a position with the hub and transverse
along the axis. This bar is interlocked by two slots or notches dia-
metrically opposite to each other made for the reception of a
key which passes through the hub and wheel as a lock pin to confine the
wheel to the axle. Both segments of the hub may be furnished with the box
and slot joint described if deemed desirable.

The interior portion of the hub in addition to the socket and connection
with the wooden wheel of a cylindrical bore surrounding the axle and ex-
tending the space in each segment. Between the socket or bore and the
bored ring or hub there is a number of radiating partitions equal
to the number of spokes in the wheel, which box and partitions are
also incorporated with and constitute portions of each segment, the
partitions extending from the bore outward to the periphery of the hub.
The segments thus formed and firmly connected by means of screws
bills in such a manner that their radiating partitions may completely
meet and contact each other to constitute the hub or hub
of the wheel. The openings or spaces between the partitions being
as receptacles for the spokes and the screw bills by which the seg-
ments are bound together passing through these receptacles are also
through the spokes. The spokes and wheel of the wheel are connected
in the usual manner of wooden wheels except in so far as relates
to the adaptation of the former to the hub. The hub or bearing

of the wheel consists of three parallel courses concentric bands or lines of wrought or malleable iron of the following description, viz 1° The flat tire or inner tire occupying the outward or inner side of the wheel rim and extending at least half the distance across it. The exterior surface of this tire presents a cylindrical or slightly taper form. The inner tire is attached to the felloes by means of iron bolts with conical heads the latter being inserted in holes of a corresponding shape made in the tire for their reception and the body of the nail or bolt being driven into or through the felloe. 2° The stepped tire is formed of a bar of wrought iron or steel whose transverse section is a square or pentagonal prism the least depth on side of which exceeds the thickness of the flat tire by at least one quarter of an inch or by a difference corresponding to the difference in lengths of the two rails of the rail way or portions of the road when the most abrupt curves or curves of the least radius occur. The width of the stepped tire should not exceed that of the flat tire and is such as to occupy that portion of the periphery of the ^{iron} ^{bar} ^{uncovered} by the flat tire. 3° The flat tire is first driven upon the iron from the face or outside of the wheel upon which the stepped tire is driven from the opposite side of the wheel into close contact with the flat tire.

Both of these tires having been applied to the wheel their exterior surfaces are dressed by burning or otherwise into the surface of the flat tire to the curvature of the road the flat tire being made cylindrical or nearly so and the stepped tire being dressed in a concave top and transversely of the wheel a gentle curve rising gradually from the surface of the flat tire and becoming more abrupt as it approaches the wheel flange. 4° The flat and stepped tires together constitute the entire wheel tread which instead of the two portions or parts of iron mentioned may be formed of a single band of wrought iron moulded into the same a similar shape with respect to its exterior surface as that presented by both portions combined.

5° The flange tire is also of wrought iron about four inches in depth and about $\frac{3}{4}$ in width in thickness this part is of a rather

the form and is applied so as to the interior of the iron side of the wheel in such a manner that the exterior flange may project about one inch beyond the sloped tire of the wheel beyond the flat tire or cylindrical part of the wheel. The flange tire is forced into close contact with the cylindrical tire, or with the main tire when a single band is used, or substituted for for the flat and sloped tires), and with the flange of the wheel by means of screw bolts passing through the flange and the flange at a suitable distance from and within the other parts of the tire. To the wheel constructed in the manner above described I give the name of the triple band wheel, where the tire of the wheel consists of three parts, viz. of the double band wheel when the two ends of the first, only as mentioned in Note 2. — The improvements described in this specification and especially claimed as new and useful are, 1st. The application of two or more horizontal cylindrical boilers to Locomotive Steam engines, with flues, leading through a portion of each and at the same time one or more flues leading in the same direction exclusively of the boilers or between them and the engine. 2nd. The use of two or more horizontal cylindrical boilers with tubular flues in connection with the fire box. 3rd. The introduction and use of steam chambers disposed in such a manner as to enlarge the steam room within the boiler, while they serve to reduce the quantity of water necessarily contained in the boiler. 4th. The construction of a grate with one or more oscillating bars, the bars to promote the combustion of Anthracite Coal ^{very} quickly. 5th. A new method of causing a grate to revolve in a circle by means of which the fire place may be speedily discharged of its contents. 6th. The construction and application of a movable or slippable ring on a view plane, and of a new method of constructing wharfs for locomotives and steam engines, all of which improvements are exemplified in the drawings, with regard to the frontispiece and are further illustrated by the following explanations and references.

Explanations of the Drawings.

Fig. 1. A horizontal section of the steam Generator on a plane.

sketching near the axis or centre of the cylindrical Boiler.

Fig. 2. A transverse vertical section of the Steam Generator passing through the fire place, grate, cylindrical steam chamber &c.

Fig. 3. A transverse vertical section of the Steam generator in the middle of the fire place and between the fire box and the smoke box.

Fig. 4. A vertical section longitudinally of the Steam generator and near the axis or centre of one of the cylindrical Boilers.

References to the Drawing and Model.

a. The fire box communicating freely with the cylindrical Boiler.

b. man holes or openings through the front of the fire box and communicating with the interior of the cylindrical Boiler.

c. The cylindrical boiler containing tubular flues, in rear of the fire place and cylindrical steam chamber within the fire box.

d. The tubular flues.

e. The steam chamber communicating with the upper part of the boiler by means of the tube e (see fig. 4)

f. Notches in the cylindrical boiler affording a communication between the fire place and the tubular flues.

g. The smoke box at the back end of the boiler. - h. the flue beneath the boiler.

i. The standing part of the chimney attached to the smoke box.

j. The slip or movable part of the chimney.

k. Screw bolts passing through the ribs of the apron and confining the same to the boiler.

l. The fire place and Grate.

m. The bars upon which the grate bars rest, one on both of, which may be oscillatory or jowable as at k.

n. The ash Pan.

o. The sides of the grate frame.

p. The apron with its ribs as at l.

q. The waste steam pipe entering vertically into the chimney.

r. The Steam pipe leading from the Boiler to the working cylinder.

7570X

C. The supply pipe for carrying water into the boiler

P. The wheel with its appropriate fixtures

I have taken up the above as a true specification of my said
improvements as abovementioned. I have countersigned my hand
and Seal this 21st day of February A.D. 1832.
